FINGER RING

Leonard Shiman, Millburn, N.J., assignor to Shiman Manufacturing Co., Inc., Newark, N.J.

Filed Apr. 5, 1971, Ser. No. 131,565

Term of patent 14 years

Int. Cl. D11—01

U.S. Cl. D45—10

FIG. 1 is a top perspective view of a finger ring showing my new design;

FIG. 2 is a side elevation thereof, the opposite side being identical thereto;

FIG. 3 is an end elevation thereof, the opposite end being identical thereto;

FIG. 4 is a top plan view thereof;

FIG. 5 is a top plan view of another embodiment of the finger ring shown in FIG. 1 having one stone mounted therein;

FIG. 6 is a top plan view of another embodiment thereof having two mounted stones;

FIG. 7 is a top plan view of another embodiment thereof having three mounted stones;

FIG. 8 is a top plan view of a further embodiment thereof having five mounted stones;

FIG. 9 is a top plan view of another embodiment thereof having six mounted stones;

FIG. 10 is a top plan view of another embodiment thereof having seven mounted stones, and

FIG. 11 is a top plan view of another embodiment having eight stones mounted thereon.

I claim:

The ornamental design for a finger ring, as shown and described.
